UNITED STATES PATENT OFFICE.

WILLIAM KANE, OF PHILADELPHIA, PENNSYLVANIA.

VALVE.

1,110,565.

Specification of Letters Patent. Patented Sept. 15, 1914.

Application filed December 1, 1913. Serial No. 803,867.

To all whom it may concern:

Be it known that I, WILLIAM KANE, citizen of the United States, and resident of Philadelphia, county of Philadelphia and 5 State of Pennsylvania, have invented an Improvement in Valves, of which the following is a specification.

The object of my invention is to provide a simple and inexpensive form of valve more 10 especially intended for use in gas burner systems, though while more particularly useful in this connection, it may be used for many purposes where a tight leak-proof valve is desired.

15 In gas valves as heretofore constructed, it has been found in practice that the plug or ground key type more generally used, is subject to constant wear as it is turned back and forth, and the effect is such as to cause 20 leakage after the valve has been in use for some time. It has also been proposed in connection with this type of valve to employ springs to take up the wear of the ground plug and to generally adjust conditions so 25 as to prevent leakage, but such devices increase the friction and wear and sooner or later there is a leakage of gas around the plug.

In my present invention I have devised a 30 construction wherein the friction and consequent wear and tear of the parts are reduced to a minimum, and wherein the valve body is made leak-proof without the aid of cumbersome stuffing box structures or like packing devices, and further, the closing movement of the valve is in a direction with the 35 gas pressure so that the latter serves as an effective auxiliary means for maintaining the valve in closed position.

40 My invention has for a further object to provide a valve operating mechanism in which the valve stem or its adjuncts are always freely movable and consequently the annoyance caused by sticking valve stems is 45 entirely eliminated.

A further object of my invention is to provide a valve structure wherein the discharged gas is proportionate to the main gas 50 pressure, and I accomplish this end by providing a novel type of adjustable needle valve which may be readily set and adapted for any particular gas pressure so that no matter what the pressure conditions may be, there is never an excessive supply to the 55 burner or burners.

Figure 1 represents a sectional elevation

of a valve embodying my invention; Fig. 2 represents a side elevation of the valve and its stem; Fig. 3 represents a plan of the valve; and Fig. 4 represents a side elevation 60 of a portion of the valve operating mechanism.

Referring to the drawings, similar numerals of reference indicate corresponding parts.

1 designates the valve body or casing which is, as usual, of hollow construction and provided with the inlet opening 2 and outlet opening 3, the said openings as here arranged being substantially at right angles 70 to each other. In addition to these openings the valve body 1 is provided with a bore 4 preferably in alignment with the inlet opening 2 and also provided with a threaded opening 5 alined with the outlet 75 opening 3.

6 designates the valve seat formed in the body 1 adjacent the inlet 2, and is adapted to be opened and closed by the valve member 7, which in the preferred form is of 80 beveled construction to conform to the general contour of the seat 6. The valve piece or member 7, as here shown, is integral with or suitably secured to a stem 8 which passes transversely through a valve body 1 by way 85 of the bore 4, from which latter it projects a suitable distance to receive a grooved spool 9 fixed to the end of the stem 8 and serving to transmit movement from a suitable operating mechanism to the said stem 8. In the present instance this spool 9 is provided with a cone-like portion 10 which is adapted 90 to seat within a counter-sunk portion 11 of the valve body 1, thus serving as a closure for the joint between the stem and the body 95 1 at the time the valve is open, to prevent leakage of gas around the stem. The spool 9 is operated in the present instance through the medium of an eccentric 12, secured to the pin 13, which latter is journaled in a

100 bracket 14 of the body 1, while the extended end of the pin has fixed thereto in any well known manner the crank arm 15 which is provided with a counterweight 16. This construction insures a positive action or 105 movement of the stem 8 in either direction, since the weighted arm 15 exerts a constant pressure under gravity upon the spool 9 either maintaining it firmly seated upon the valve body to prevent leakage through the 110 joints, or holding the valve piece firmly seated in closed position.

It will be noted that the valve adjuncts are so positioned and arranged that the pressure of the gas acts as an auxiliary means to hold the valve piece 7 in closed position so that after a closing movement of the valve stem 8 by throwing the weighted arm in the proper direction, the aforesaid pressure will tend to maintain it in closed position, thus eliminating the danger of leakage irrespective of the valve position.

In the present embodiment of my invention I have provided a slot 17 at a suitable point in the stem 8 for the purpose of allowing free movement therethrough of a needle valve stem 18, this latter having the customary cone-shaped end 19 at one end while its opposite end I have shown provided with a screw thread 20. The threaded end 20 is in engagement with a closure or cap 21 threaded into the opening 5 to effectually close the same so that there is no opportunity for the gas to leak at this point. The needle valve 18 is normally open a predetermined distance which may be varied according to the pressure of the main gas supply, and after it is once adjusted by turning it with respect to the closure 21 it remains permanently fixed in this position and the supply of gas through the opening will consequently be in proper proportion to the gas pressure.

As here shown I have formed the needle opening or gas outlet 22 in the end of a cap nipple 23 which is threaded into the outlet opening 3 of the valve body, and the gas therefor entering through the inlet 2 and passing by way of the valve seat 6 is discharged through the needle opening 22.

In the operation of this valve it will be noted that when the valve 7 is open and gas is flowing through the body, there is no chance of leakage through any of the joints since the opening 5 is tightly sealed by the closure 21, and the joint between the stem 8 and the body 1 is perfectly sealed by the spool 9 under the constant pressure of the arm 15 under the action of gravity. When the valve 7 is closed and correspondingly the bushing 9 has moved away from the body 1, the aforesaid joint of the stem 8 is not subject to the gas pressure owing to the fact that the valve 7 is seated and so held by the pressure in the rear of the valve, together with the weight of the arm 15. Attention is further directed to the fact that the parts are so arranged that there is little wear, the friction is reduced to a minimum and in view of the gravity controlled operating mechanism for the stem 8 there can be no sticking of the valve stem or its adjuncts.

It will further be apparent that a very slight movement of the arm 15 out of the vertical will cause it to drop by gravity action, thus promptly shifting the valve to

open or closed position as the case may be.

While I have described my invention in the form which I prefer in practice, the minor details may be modified without departing from the spirit of the invention.

Having thus described my invention, what I claim and desire to secure by Letters Patent is

1. In a device of the character stated, a hollow valve body having an inlet and an outlet therein, a valve member adapted to control said inlet, a stem secured to said valve member and projecting exterior of said valve body, means connected to the extended portion of said stem for causing said valve to shift from one position to another, and means independent of the valve and its operating means to proportion the area of said outlet in accordance with the pressure at said inlet, said proportioning means being normally concealed within said valve body.

2. In a device of the character stated, a hollow valve body having an inlet and an outlet therein, a valve member adapted to control said inlet, a stem secured to said valve member and projecting exterior of said valve body, means connected to the extended portion of said stem for causing said valve to shift from one position to another, said means embodying a gravity actuated mechanism, a needle valve adjustably mounted within said valve body for varying the area of said outlet in accordance with the pressure at said inlet, and means for fixing said needle valve in adjusted position and concealing said needle valve within said valve body.

3. In a device of the character stated, a hollow body having an inlet and an outlet therein, a valve member adapted to control said inlet, a stem secured to said valve member and projecting exterior of said valve body, said stem being slidably mounted in said body and having a slot therein, gravity controlled means for positively shifting said valve from one position to another, a needle valve passing through said slot and adjustably mounted for varying the area of said outlet, and means secured to said valve body for fixing said needle valve in adjusted position, and concealing said needle valve within said body.

4. In a device of the character stated, a hollow valve body having an inlet and an outlet therein, a valve member adapted to control said inlet, a stem secured to said valve member and projecting exterior of said valve body, means carried by the extended end of said stem for sealing the joint between said stem and said valve body in open position of said valve, means connected to the extended portion of said stem, for causing said valve to shift from one position to another, said means embodying

a gravity actuated mechanism for positively actuating said stem and holding the same fixed in either open or closed position of said valve, a needle valve adjustably mounted in said valve body for varying the area of said outlet in accordance with the pressure of said inlet, and means for fixing said needle valve in adjusted position and concealing said needle valve within said valve body.

5. In a device of the character stated, a hollow valve body having an inlet and an outlet therein, a valve member adapted to open and close said inlet, a stem for said valve member slidably mounted in said valve body, said parts being arranged so that the pressure is back of the valve in closed position, said stem projecting exterior of said valve body and having a slot 20 therein in alignment with said outlet, a grooved spool fixed to the extended portion of said stem, an eccentric mechanism operating in said groove to shift said stem in either direction, a weighted arm secured to said extension for positively actuating said parts and holding said valve in either open or closed position, a needle valve adjustably mounted within said valve body and passing through said slot, and means for fixing said 25 needle valve in adjusted position and concealing said needle valve within said valve body.

6. In a valve, the combination of a body having inlet and outlet ports, with a valve

device for controlling the inlet port having 35 operative means extending to the outside of the body, a needle valve to control the outlet port arranged within the body and adjustable to and from the outlet port, and a removable plug extending through the 40 wall of the body and having on its inner end an adjustable connection with the needle valve, whereby the needle valve may be adjusted and is normally shielded from being tampered with.

7. In a valve, the combination of a body having inlet and outlet ports, with a reciprocable valve device for controlling the inlet port, having operative means comprising a stem extending to the outside of the 50 body, a needle valve to control the outlet port arranged within the body and extending transversely to the stem of the valve device but without contact therewith, and adjustable to and from the outlet port, and a 55 removable plug extending through the wall of the body and having on its inner end an adjustable screw connection with the needle valve, whereby the needle valve may be adjusted and is normally shielded from being 60 tampered with.

In testimony of which invention, I hereunto set my hand.

WILLIAM KANE.
